UNITED STATES PATENT OFFICE.

WILLIAM F. WOLF, OF SOMERVILLE, NEW JERSEY.

CENTRIFUGAL CASTING MACHINE.

1,415,421.

Specification of Letters Patent.

Patented May 9, 1922.

Application filed April 30, 1921. Serial No. 465,810.

To all whom it may concern:

Be it known that I, WILLIAM F. WOLF, a citizen of the United States, and resident of Somerville, county of Somerset, and State 5 of New Jersey, have invented certain new and useful Improvements in Centrifugal Casting Machines, of which the following is a specification.

The object of the present invention is to 10 provide a simple and efficient centrifugal casting machine for producing cylindrical, tubular castings, such, for instance, as are formed as a preliminary step in the manufacture of piston rings. The improved machine 15 has been designed for convenience in operation as well as for its efficiency in the production of castings of uniform thickness and density.

In order that my invention may be fully 20 understood, I will first describe the same with reference to the accompanying drawings, and afterward point out the novelty of the same in the annexed claims. In said drawings:—

25 Figure 1 is a vertical, sectional view of my improved centrifugal casting machine.

Figure 2 is a side elevation of the same.

Figure 3 is a horizontal, sectional view, taken on the line 3—3 of Figure 1.

30 Figure 4 is a top plan view of the cap piece.

Figure 5 is a side elevation of the fixed mold-supporting pot of the rotary table.

35 Figure 6 is a side elevation of a slightly modified form of casting machine embodying my invention.

40 Mounted in suitable bearings of a frame 1, is a vertical rotary shaft 5 resting upon the step bearing 2 and carrying between its ends a driving pulley 3. The pulley 3 is driven by a belt 6 passing around idler pulley 7 journalled upon studs 8 carried by a bracket 9. The driving belt 6 is operated by a driving pulley 10, mounted upon the power 45 shaft 11.

Rigidly secured and keyed to the upper end of the vertical shaft 5 is a rotary table or platform 15, upon which is secured an upright mold-receiving pot 20 formed with 50 integral lugs or feet 21, through which extend the securing bolts 22 that fasten the pot 20 to the table 15. The pot 20 has a central sustaining foot or lug 23 for strengthening its bottom wall. The pot 20 is also formed 55 with diametrically opposite vertical slots 24 in its cylindrical side wall at its upper edge

to receive the radial handle lugs 31 of a removable mold-supporting pot 30. This pot 30 is of cylindrical shape, having a closed bottom designed to fit the fixed pot 20, the engagement of the lugs 31 with the slots 24 causing the removable pot 30 to rotate accurately with the table 15 and pot 20.

The removable pot 30 is preferably provided with a removable lining shell 35 with in which is molded the sand core 40, against which the casting is to be made. The core 40 is preferably counterbored on a slight taper at its upper end for the purpose of forming a slightly thickened ring on the 70 end of the cylindrical casting for convenience in handling in the lathe.

50 is a shaft journalled in suitable, paired bracket bearings 51 at the base of the machine and 52 are eccentrics keyed to the 75 shaft 50 within the bearings 51. 55 is a hand lever by which shaft 50 and eccentrics 52 can be operated. The eccentrics 52 are encircled by straps 56 fixed upon the lower sections of two upwardly projecting sectional rods 57 which pass through openings in guide brackets 58 and extend upon opposite sides of the rotating table 15 and pot 20. The brackets 51 and 58 referred to may be separate brackets properly bolted to the 85 floor or other foundation or they may be parts of a complete frame suitably braced and arranged to sustain the operating parts of the machine. The sections of the rods 57 are connected by knuckle joints to permit 90 the upper and lower sections to move transversely upon the central guided section so as to allow freedom of movement of the straps 56 at the lower end and freedom of movement of the upper sections carrying the cap 95 piece, which will now be referred to.

The ends of the upper sections of rods 57 are threaded at 57* and passed through suitable openings in a yoke-shaped cap plate 60 which is formed with a central pouring 100 opening 61 and is rigidly attached to the sectional rods 57 by means of nuts 62 screwed upon the rods 57 and adjustably holding the cap plate in position thereon.

65 is a casting regulating ring formed 105 with an annular, downwardly presented flange 66 adapted to enclose the upper edge of the fixed pot 20 and an inwardly presented annular flange 67 that projects inwardly over the upper edge of the fixed pot 20 and 110 the sectional mold comprising the removable pot 30, lining 35 and sand core 40. The in-

ner edge or lip of this horizontal flange 67 determines, by its extent of projection over the open upper end of the sand core, just how thick the casting will be. The cap ring 65 is securely fastened to the under face of the yoke 60 by means of set screws 68, said ring being concentric with the pouring opening 61 of yoke 60 and also concentric with the sectional mold when in position thereon. The central opening or cavity of the cap ring 65 is of sufficiently larger diameter compared with the pouring opening 61 of yoke 60 to form between the cap and yoke an annular chamber, indicated at 69, into which any surplus molten metal poured 15 into the mold will collect as it flows over the determining lip 67 of the regulating ring.

In Figure 6 of the drawings, I have shown a slight modification in which the rotating 20 table 15^a, carrying the fixed pot 20^a, is mounted upon a shaft which extends at an angle of 45 degrees and is supported in bearing brackets 2^a. The arrangement of driving belt 6^a and pulleys 3^a, 7^a and 10^a is slightly 25 modified to suit the changed angle of the machine. The cap plate or yoke 60^a is secured upon sectional rods 57^a actuated by eccentrics 52^a and hand lever 55^a, while a counterbalancing weight 80, attached to a 30 cord or cable 81 passing around guide pulley 82 provided with a hook 83, engages the flange on the cap plate so that when the cap plate and attached regulating ring 65^a are 35 disengaged from the sectional mold, they can be readily moved upwardly by the assistance of the counterweight and be sustained in disengaged position for the mounting or removal of the mold. It will be observed from this modification that the rotating 40 casting machine may be mounted to operate at any desired angle.

The operation of the improved machine will be understood with the following brief explanation with particular reference to the 45 preferred form shown in the first five figures of the drawings. With the cap piece removed, as indicated in dotted lines, the removable pot 30, containing the cylindrical lining 35 and molded sand core 40, is placed 50 into the fixed pot 20 with the handle lugs 25 engaging the slots 24. The cap piece is then moved over into position above the sectional mold and by operation of the handle 55 moved downwardly into close relation thereto. The power is then thrown on to rotate the table carrying the sectional mold, the rapidity of rotation depending upon the character of the casting to be formed and the molten metal of approximately the 60 proper quantity is poured into the rotating mold through the pouring opening 61. The metal forming upon the inner surface of the sand core 40 rises to a uniform thickness and density, the thickness depending upon the 65 amount of projection of the lip 67 of the

regulating ring 65, it being understood that any surplus of metal will flow over the lip and collect in the chamber 69. When the casting has been completed, the cap piece is released from the sectional mold and thrown 70 over to one side, as indicated, when the mold with casting can be removed from the machine and the casting separated from the mold.

I claim:—

1. In a centrifugal molding machine, the combination of a rotary mold, with a non-rotating cap piece movable into and out of fixed operative relation with the open end of said mold and formed with a pouring 80 opening and an inwardly presented annular flange or lip.

2. In a centrifugal molding machine, the combination of a rotary mold, with a non-rotating cap piece adjustably mounted in 85 fixed operative relation to the open end of said mold, said cap piece having a central pouring opening and a casting regulating ring formed with an inwardly presented annular flange or lip.

3. In a centrifugal molding machine, the combination of a rotary mold, with a cap piece movable into and out of operative relation with the open end of said mold and formed with a pouring opening and an annular chamber for collecting surplus molten 95 metal.

4. In a centrifugal molding machine, the combination of a rotary mold, with a cap piece movable into and out of operative relation with the open end of said mold and having a central pouring opening, a casting regulating ring formed with an inwardly presented annular flange or lip, and an annular chamber for collecting surplus molten 105 metal.

5. In a centrifugal molding machine, the combination of a rotary mold, with a cap piece movable into and out of operative relation with the open end of said mold and formed with a central pouring opening, a casting regulating ring secured to the under face of said cap piece and formed with an inwardly presented annular flange or lip, and an annular chamber between the ring 115 and cap piece for collecting surplus molten metal.

6. In a rotary casting machine, the combination of a rotatable table arranged to support a mold, a cap piece cooperating with the mold upon said table, sectional rods upon which said cap piece is adjustably mounted, guides for said rods, a shaft carrying eccentrics, straps mounted upon said sectional rods and engaging said eccentrics, and a 120 hand lever for operating said eccentrics.

7. In a rotary casting machine, the combination of a rotatable table arranged to support a mold, a cap piece cooperating with the mold upon said table and having a 125

- central pouring opening and a casting regulating ring formed with an inwardly presented annular flange or lip, sectional rods upon which said cap piece is adjustably mounted, guides for said rods, a shaft carrying eccentrics, straps mounted upon said sectional rods and engaging said eccentrics, and a hand lever for operating said eccentrics.
8. In a rotary casting machine, the combination of a rotatable table, a mold supporting pot formed with wall slots and fixed to said table, a removable mold-supporting pot adapted to fit said fixed pot and having radial lugs or arms engaging the slots of said fixed pot, a sand core mounted in said removable pot, a casting regulating cap plate, and means for supporting the cap plate in operative relation to said pots.
9. In a rotary casting machine, the combination of a rotatable table having a mold-supporting pot fixed thereto, a removable mold-supporting pot adapted to fit said fixed pot, a removable cylindrical lining
- 5 mounted in said removable pot, a sand core molded in said lining, a cap plate carrying a casting regulating ring formed with a downwardly presented flange, sectional rods upon which said cap piece is mounted, and hand operated means, including eccentrics, engaging said rods for moving said cap piece into and out of position.
10. In a rotary casting machine, the combination of a rotatable table having a mold-supporting pot fixed thereto, a removable mold-supporting pot adapted to fit said fixed pot, a sand core mounted in said removable pot, a cap plate carrying a casting regulating ring formed with an inwardly projecting, annular flange or lip and a downwardly presented annular flange, sectional rods upon which said cap piece is mounted, and hand operated means, including eccentrics, engaging said rods for moving said cap piece into and out of position.

WILLIAM F. WOLF.
